COMPRESSOR

Filed May 10, 1926

UNITED STATES PATENT OFFICE.

PELLE ANDERSSON, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

COMPRESSOR.

Application filed May 10, 1926. Serial No. 107,907.

This invention relates generally to new and useful improvements in the construction and operation of air compressors or the like, and relates more specifically to improvements in air compressor valve structures and to improved instrumentalities co-operating with one or more of the valves to unload the compressor.

An object of the invention is to provide an improved compressor valve structure which is simple in construction and efficient in operation. Another object of the invention is to provide a new and useful unloading device especially applicable to air or gas compressors. These and other objects and advantages will be apparent from the following description.

Some of the novel features of valve structure disclosed but not specifically claimed herein, form the subject of a divisional application filed January 18, 1929.

A clear conception of several embodiments of the novel features and of the operation of devices embodying the invention, may be had by referring to the drawing accompanying and forming a part of this specification in which like reference characters designate the same or similar parts in the various views.

Fig. 1 is a somewhat diagrammatic and part sectional side elevation of a compressor cylinder, the section being taken adjacent to one of the inlet valves.

Fig. 2 is an enlarged sectional view of one of the compressor inlet valves showing the unloading mechanism associated therewith.

Fig. 3 is an enlarged sectional view of one of the compressor inlet valves having a modified form of unloading mechanism associated therewith.

The compressor to which the invention has been specifically applied herein, is of the constant speed type and comprises a cylinder 2 having therein a usual form of reciprocable piston, and also having end heads 3, 4 within which are located inlet and exhaust valves communicating with the air supply and discharge conduits 36, 37 respectively. The compressor piston may be reciprocated in any convenient manner, as by an electric motor, and the pressure of the compressed air delivered through the discharge conduits 37 varies according to

the demand for air at the source of utilization.

The improved inlet valve structure shown in Figs. 2 and 3, comprises an annular sheet metal or plate valve 18 which is constantly urged toward an annular seating 24 formed on the seating element 20, by means of one or more springs 19 which react against a valve stop 17. The valve stop 17 is rigidly secured to the seating element 20 by means of a clamping bolt 21, and has a recess formed to receive the valve 18 when in open position, so that the discharge edge of the valve 18 is completely surrounded by an annular lip 23 when the valve is fully open.

The improved unloading device shown in Fig. 2, comprises a bridge piece or member 16 movably supported from the seating element 20 by means of parallel links 15, 25, and is disposed between the valve 18 and a positioning cam 14. The links 15, 25 are

mounted to swing about upper fixed pivots 75 and have their lower ends pivotally associated with lower pivots secured to the bridge member 16, thereby causing the contact surface of the member 16 to always assume parallel positions. The bridge member 16 carries a roller 35 which is held in engagement with one of the surfaces 38, 39, 40 of the cam 14 by means of a spring 22 which reacts against the seating element 20. The cam 14 is supported upon a cam shaft 11 and has an arcuate unloading surface 38, a second arcuate bridge releasing surface 39 of shorter radius than that of the surface 38, and an intermediate surface 40 connecting the surfaces 38, 39, all of the surfaces 38, 39, 40 being adapted to engage the roller 35 at certain times. The cam shaft 11 is angularly adjustable and oscillatable during operation of the compressor, by means of a rocker arm 13 and a connection 9, in a manner to be later explained.

The modified unloading device shown in Fig. 3, comprises a bridge piece or member 26 movably suspended from the cylinder head 4 and from an extension on the seating element 20, by means of an arm 27 formed integral with the member 26. The arm 27 is pivotally supported at its upper end and carries a roller 35 at its lower extremity, which cooperates with the surfaces 38, 39, 40 of the adjacent cam 14.

The remainder of the unloading device of Fig. 3 is substantially similar to that of Fig. 2, both in structure and mode of operation, but the contact surface of the member 26 does not move to parallel positions.

The actuating mechanism for the unloading devices, comprises a regulator 5 mounted laterally adjacent to the cylinder 2 and consisting of an auxiliary cylinder having 10 therein a vertically movable plunger 29. A pipe 28 provides a connection from the discharge conduit 37 or other pressure source, to the oil chamber within the regulator casing, and this oil chamber communicates with the plunger chamber past a needle valve 41. The plunger rod 30 is adapted to transmit motion to levers 31 which are in turn adapted to adjust the T-lever 7 about its supporting pivot 33, 20 through a connection 32. The supporting pivot 33 of the T-lever 7 is associated with the lower swinging end of the oscillatory lever 6 the upper end of which is supported by a fixed pivot 42. The lever 6 is swingable back and forth during normal operation of the compressor, by means of a connection 34, and the upper and lower arms of the T-lever 7 are joined to the rocker arms 12, 13 by means of connections 8, 9 30 respectively. As previously explained, the rocker arms 12, 13 are secured to the cam shafts 10, 11 carrying the unloading cams 14.

During normal operation of the compressor, the piston is being reciprocated to alternately draw air into and discharge air from the opposite ends of the cylinder 2 through the inlet and discharge conduits 36, 37. The connection 34 is being reciprocated simultaneously with the reciprocation of the piston, thus producing oscillation of the lever 6 about the pivot 42 and causing the T-lever 7 to rock with the lever 6. The rocking motion of the T-lever 7 is transmitted through the connections 8, 9 and the arms 12, 13 to the cam shafts 10, 11 thus producing periodic rocking movement of the cams 14. When the cam 14 is in the position shown in Fig. 2 with 40 the cam surface 38 engaging the roller 35 of the adjacent bridge member, throughout the rocking movement, the bridge member holds the inlet valve 18 in open position throughout the compression stroke and the compressor is fully unloaded. When 50 the cam 14 is in the position shown in Fig. 3 with the cam surface 39 in engagement with the roller 35 of the bridge member, throughout the rocking movement, the bridge member does not engage the inlet valve 18 and this valve functions normally to admit air to the cylinder on the suction stroke and to prevent escape of air past the valve on the return stroke. 60 By proper adjustment of the position 65

of the cams 14, unloading may obviously be effected during any desired portion of the compression stroke. Such adjustment of the cams 14 may be automatically accomplished in accordance with variations 70 in the discharge pressure or of any other variable operating characteristic, by means of the regulator 5. As the pressure admitted through the pipe 28 increases, the plunger 29 and rod 30 move upwardly thereby causing the cam surfaces 38 to become effective and increasing the duration of the unloading action, and vice versa.

With the construction shown in Figs. 1 and 2, the contact surface of the bridge member 16 is always advanced to parallel positions by virtue of the parallel links 15, and always has surface engagement with the valve 18 when the unloader is effective. While the construction shown in Fig. 3 does not produce such parallel positioning of the contact surface, the relatively long supporting arm 27 allows but slight angular displacement of this surface resulting in slight tilting of the valve 18.

The lip 23 surrounding the valve 18 prevents the air which returns to the inlet conduit 36 during unloading, from returning the valve to its seating 24 thereby producing highly efficient unloading. The annular sheet metal or plate valves 18 are of simple construction and have proven highly efficient in operation.

It should be understood that it is not desired to limit the invention claimed to the exact details of construction shown and described, for obvious modifications may occur to persons skilled in the art.

It is claimed and desired to secure by Letters Patent:

1. In a compressor, a cylinder, an inlet valve for controlling admission of air to said cylinder, means for constantly urging said valve toward closed position, a member adapted to hold said valve in open position, a cam for adjustably positioning said member, and means for continuously rocking said cam during operation of the compressor.

2. In a compressor, a cylinder, an annular sheet metal inlet valve for controlling admission of air to said cylinder, spring means for constantly urging said valve toward closed position, a bridge member adapted to prevent said valve from seating, a cam for adjustably positioning said member, and means for continuously rocking said cam during operation of the compressor.

3. In a compressor, a cylinder, an inlet valve for controlling admission of air to said cylinder, means for constantly urging said valve toward closed position, a member adapted to hold said valve in open position, a cam for adjustably positioning said member, means for varying the position of said cam in accordance with variations in the

discharge pressure, and means for rocking said cam during operation of the compressor.

4. In a compressor, a cylinder, an annular sheet metal inlet valve for controlling admission of air to said cylinder, spring means for constantly urging said valve toward closed position, a bridge member adapted to prevent said valve from seating, a cam for adjustably positioning said member, means for varying the position of said cam in accordance with variations in the discharge pressure, and means for rocking said cam during operation of the compressor.

5. In a compressor, a cylinder, an inlet valve for controlling admission of air to said cylinder, means for constantly urging said valve toward closed position, a member adapted to hold said valve in open position, a cam for adjustably positioning said member, means or adjusting said cam in accordance with variations in the discharge pressure, and means or continuously rocking said cam during operation of the compressor.

25 6. In a compressor, a cylinder, an annular sheet metal inlet valve for controlling admission of air to said cylinder, spring means

for constantly urging said valve toward closed position, a bridge member adapted to hold said valve in open position, a roller 20 carried by said bridge member, a cam co-acting with said roller for adjustably positioning said member, means for adjusting the position of said cam in accordance with variations in the discharge pressure, and 35 means for rocking said cam during operation of the compressor.

7. In a compressor, a cylinder, an annular sheet metal inlet valve for controlling admission of air to said cylinder, spring means 40 for constantly urging said valve toward closed position, a bridge member adapted to hold said valve in open position, a roller carried by said bridge member, a cam co-acting with said roller to hold said valve in 45 open position, spring means for urging said member toward said cam, means for adjusting the position of said cam in accordance with variations in the discharge pressure, and means for rocking said cam during 50 operation of the compressor.

In testimony whereof, the signature of the inventor is affixed hereto.

PELLE ANDERSSON.
